UNITED STATES PATENT OFFICE.

HENRY H. CHOTEAU, OF TOPEKA, KANSAS, ASSIGNOR OF ONE-FOURTH TO FRANK R. WILSON, ONE-FOURTH TO LAURA WILSON, AND ONE-FOURTH TO OGEAL SMITH, ALL OF TOPEKA, KANSAS.

PROTECTOR FOR LIGHT-GLOBES.

1,216,074.

Specification of Letters Patent. Patented Feb. 13, 1917.

Application filed July 22, 1916. Serial No. 110,737.

To all whom it may concern:

Be it known that I, HENRY H. CHOTEAU, a citizen of the United States, residing at Topeka, in the county of Shawnee and 5 State of Kansas, have invented certain new and useful Improvements in Protectors for Light-Globes, of which the following is a specification, reference being had to the accompanying drawings.

10 This invention relates to a device for holding light globes in place and particularly to devices for holding the practically spherical globes used to a large extent for street lighting.

15 The general object of my invention is the provision of a device which will securely hold the globe in place on the lamp post and will protect it from damage during severe snow storms, and a further object 20 of this invention is to provide a protector which while securely holding the globe in place may be readily detached so as to permit the removal of the globe from its operative position.

25 Other objects will appear in the course of the following description.

My invention is illustrated in the accompanying drawings, wherein:

Figure 1 is an elevation partly in section 30 of my invention in applied position; and Fig. 2 is a fragmentary section on the line 2—2 of Fig. 1.

In the drawings, A designates a post and B a spherical light globe of any ordinary or 35 usual construction. This globe has a neck which is disposed in a socket 10 mounted upon the post, this socket having an up-standing flange, the flange being provided with screw-threaded openings at a plurality 40 of points. The protector comprises a band 11 which may be made of copper, brass, or other suitable material, this band being relatively light and having a diameter less than the greatest diameter of the globe so that 45 when the band is in place, it will seat upon the globe about one-third from the top. The band 11 is formed at a plurality of points with recesses or openings 12. As illustrated, there are four of these openings 12. Swing- 50 ingly mounted upon the band are a plurality of vertically disposed strips 13, the upper ends of which are bent to engage

with the band, the openings 12 being provided so that the strips 13 may swing or have a hinged engagement with the band. 55 The lower ends of the strips 13 are formed with eyes 14 or apertures, through which the screws 15 are adapted to pass, these screws being engaged in the screw-threaded openings of the flange of the socket 10. 60 The strips 13 are of course curved to conform to the curvature of the globe B.

The practical use of my invention will be obvious from the drawing. When the protector is in place, it will clamp the globe 65 firmly to its socket and prevent any detachment of the globe, and consequent breakage, even under great wind pressure. In order to remove the protector it is only necessary to release the set screws 15 whereupon the 70 band 11 may be readily lifted from the globe. If it be desired to remove the globe and the protector together, the set screws 15 are released whereupon the globe may be lifted off out of its socket with the pro- 75 tector. It is obvious that my protector may be so formed as to add to the ornamental character of the lamp and it may be made of any suitable material.

Having described my invention, what I 80 claim is:

1. A light globe protector comprising a circular band having a diameter less than the greatest diameter of the globe to which it is to be applied and having a plural- 85 ity of strips extending downward from it and provided with screws, said strip being hinged to the band.

2. The combination with a support having a socket, and a lamp globe fitting in 90 said socket, of a protector for the globe comprising a circular band less in diameter than the greatest diameter of the globe, and engaging the upper portion of the globe, and strips hinged to and extending downward 95 from the band conforming to the curvature of the globe and detachably connected to the socket.

In testimony whereof I hereunto affix my signature in the presence of two witnesses. 100

HENRY H. CHOTEAU.

Witnesses:

S. R. McClure,
R. E. Lewis.
